UNITED STATES PATENT OFFICE

95,475

DESIGN FOR A GAME APPARATUS

Edward J. Wohlfeld, Indianapolis, Ind.

Application March 2, 1935, Serial No. 55,693

Term of patent 3½ years

To all whom it may concern:

Be it known that I, Edward J. Wohlfeld, a citizen of the United States, residing at Indianapolis, in the county of Marion and State of Indiana, have invented a new, original, and ornamental Design for Game Apparatus, of which the following is a specification, reference being had to the accompanying drawing, forming part thereof.

The figure is a perspective view of a game apparatus, the legs being partly broken away for convenience in illustration, showing my new design. The ornamentation on the opposite end and side of the apparatus is the same as that shown.

I claim:

The ornamental design for a game apparatus, as shown and described.

EDWARD J. WOHLFELD.
